PUMP

Andrew O. McCollum, Detroit, Mich., assignor of
one-half to Orla H. McCollum, Detroit, Mich.

Application June 9, 1936, Serial No. 84,345

2 Claims. (Cl. 103—120)

This invention relates to a pump and more particularly to a pump adapted to deliver a supply of liquid under a variable pressure at constant speeds of the pump, or to deliver a constant supply of liquid at variable speeds of the pump.

In certain applications of a pump, as for example where the consumption of the liquid supplied is variable, it is desirable to supply the liquid in such quantities as is used thus necessitating a variable supply of liquid at constant speeds of the pump. In other instances it is desirable to maintain a constant pressure of the liquid while the speed of the pump is variable, as for example in the oil pump of an internal combustion engine when a constant pressure on the bearings is desired. However, it is sometimes desirable to vary the pressure of the liquid in proportion to the speed of the pump, as a greater pressure may be required at higher speeds than at lower speeds.

Heretofore by-passes or relief valves have been used and in some cases specially designed valves have been used in the by-pass passage to obtain variable supplies at constant speeds or constant supplies at variable speeds. Such devices are expensive and necessitate many parts particularly where a variable pressure in proportion to a variable speed is required.

It is therefore an important object of this invention to provide a pump which is adapted to deliver a liquid at a constant supply, the pressure of the supply affecting the pumping action of the pump. More specifically stated, the invention contemplates using the pressure built up by the pump to regulate the amount of liquid drawn into the pump. In one application of my device in which a pair of meshed gears are used, the liquid on the pressure side of the pump is adapted to move one of the gears axially thereby making them more or less efficient depending on the pressure of the liquid.

Another object of the invention is to provide adjusting means for regulating the relative movement of the pumping members. The adjusting means in the preferred form is resilient or yielding in which case the pressure of the liquid may be maintained practically constant or made to vary in proportion to the speed of the pump, depending on the type of yielding or resilient means employed and the static loading thereof.

The above and other novel features of the invention will appear more fully hereinafter from the following detailed description when taken in conjunction with the accompanying drawing. It is expressly understood, however, that the drawing is employed for purposes of illustration only

and is not designed as a definition of the limits of the invention, reference being had for this purpose to the appended claims.

In the drawing, wherein similar reference characters refer to similar parts throughout the several views:

Figure 1 is a sectional view of a pump illustrating a preferred form of my invention;

Figure 2 is a side elevation of the form shown in Figure 1;

Figure 3 is a sectional view taken on line 3—3 of Figure 1;

Figure 4 is a view showing in elevation a modified form of adjusting means for regulating the pumping means shown in Figure 1;

Figure 5 is a view illustrating the application of my invention to another type of pump in which an eccentric is used, parts being broken away and the cover removed;

Figure 6 is a sectional view taken on line 6—6 of Figure 5 showing the cover as applied thereto;

Figure 7 is a sectional view showing another modification of my invention in which an adjustable weight may be used for regulating the pumping means to obtain a constant supply at variable speeds of the pump; and

Figure 8 is a sectional view on line 8—8 of Figure 7.

Referring to the illustrated embodiment of my invention and particularly to Figure 1, there is provided a two-part casing consisting of a head portion 10 and a base portion 12, there being provided flanges 14 on each portion secured together by screws 16. The base portion 12 is also provided with an attaching flange 18 which may be used to secure the assembly to a support. A chamber is provided in the base which, in the form shown in Figures 1, 2, and 3, is formed by two overlapping parallel bores 20 and 22. The head portion is provided with a bearing portion 24 in the form of an extended boss and a screw-threaded opening 26. When the cover 10 is secured to the base 12, the bearing 24 and the opening 26 are axially aligned with the bores 20 and 22 respectively.

A driving shaft 28 is journalled in the bearing 24 and extends into the bore 20. Mounted on the lower end of the shaft 28 is a cylindrical member 30 which slidably fits the inner periphery of the bore 20 and a portion of which extends into the bore 22. A boss 32 on the cover 10 is adapted to fit the upper end of the bore 20 and is provided with a circular groove or cut-away portion 34, the periphery of which completes and forms a portion of the inner periphery of the bore 22.

at its upper end. A rotor of the same diameter as the bore 20, shown in this form as a toothed gear 36, is keyed to the shaft 28 as at 38 and is placed between the inner ends of the boss 32 and the member 30. It will be understood that the shaft 28, member 30 and gear 36, when assembled in the cover, form a unit and that the inner ends of the boss 32 and member 30 seal the edges or side faces of the gear forming liquid spaces between the teeth of the gear.

Axially movable in the bore 22 is another rotor or toothed gear 40 of the same diameter as bore 22 which meshes with and is driven by the gear 36. On one side of the gear 40 there is provided a circular disc member 42 which slidably fits the bore 22 and groove or cut-away portion 34 in the boss 32. On the other side of the gear 40, and in contact therewith there is provided a cylindrical member 44 having a circular groove or cut-away portion 46 which fits around the outer periphery of the member 30. The members 42 and 44 and the gear 40 are carried by a shaft 48 which may be an integral part of the member 42 and pinned to the member 44 as at 50 to prevent rotation. The gear 40 is free for rotation on the shaft 48 and the parts assembled form a unit free for axial movement within the bore 22. An elemental passage or groove 52 is provided in the member 44 which forms a communication from the gear teeth circle on the gear 40 at a point angularly displaced from where the gear teeth mesh, so that fluid may exert a piston pressure on the end face of the member 44, urging the same upward as illustrated in Figure 1, the under end surface of the member 44 and shaft 48 forming a piston.

Threaded in the opening 26 is a screw 54 which adjustably tensions a spring 56 between the lower end of the screw and the upper surface 40 of the circular disc member 42. A cap 58 may be provided over the outer end of the screw 54 serving as a lock to retain the screw in adjusted position.

An inlet opening 60, communicating with the chamber formed by the two bores 20 and 22, admits liquid to the gears and they carry the liquid around, each in opposite directions, to the opposite side of the chamber where the liquid is delivered out through outlet opening 62; the meshing of the gears preventing a return of the liquid to the inlet opening 60. At this point, it should be noted that the passage 52 in reality communicates with the outlet opening 62, and that the circular disc 42 is provided with a passage 64 forming a communication between the inlet opening 60 and the upper exposed face of the disc.

In the operation of this form of my device a pressure is built up on the outlet side of the meshed gears. The pressure is conducted through the passage 52 and below the member 44. When this pressure at this point becomes greater than the tension on the spring 56, previously adjusted to the proper tension, it moves the unit comprising member 42, gear 40 and member 44 axially upwardly, reducing the engaging surface of the gears and reducing the pumping action. In effect it is the same as reducing the thickness of both gears. The groove 64 is provided in the member 42 to permit escapement of air or liquid which might be otherwise entrapped in the upper end of the bore 22. The passage 52 is on the pressure side of the chamber and the groove 64 is on the intake side of the chamber.

This construction permits a variable supply of

liquid in proportion to the speed of a variable drive, and with the use of a highly loaded spring, may give a substantially uniform supply regardless of speed.

If it is desired to make the device so that the effective width of the gears may be adjusted, the screw 54 and spring 56 may be replaced by a screw 66 and a link 68 as shown in Figure 4. A ball and socket joint connects the link to the member 42' and the link 68 is secured to or a part of the screw 66. It will be understood that by turning the screw 66 the gear 40' may be raised or lowered thereby reducing or increasing the effective width of the gears or their pumping action. This form of the invention is best adapted for delivering a variable at will constant supply of liquid at a constant speed.

In Figures 5 and 6, there is shown an eccentric pump with a form of the present invention applied thereto. The casing comprises a head portion 70 and a base portion 72, each having flanges 74 adapted to be secured together by screws 76. A chamber is provided in both members the same being divided by a slidably plate 78 forming a chamber 80 and a chamber 82. A slot 84 is formed in the wall of the chamber 82 to receive a sliding plate 86 resiliently urged toward the center of the chamber by a flat Z spring 88.

A driving member 90 is journaled in the base 72 and is in axial alignment with the chamber 82. At the inner end of the driving member 90 is a pin 92 eccentrically mounted thereon. Slidably mounted on the pin 92 and extending through an opening in the plate 78 is a cylindrical member 94. The plate 86 is resiliently urged against the outer periphery of the member 94 forming compartments 96 and 98. An inlet opening 100 and an outlet opening 102 are provided in the base 72 and are on opposite sides of the plate 86 and slot 84.

It will be understood that as the driving member is rotated the compartments 96 and 98 increase and decrease in volume due to the eccentric movement of the member 94, and pump the liquid.

Mounted in the cover and in axial alignment with the driving member 90, there is illustrated a plunger 104 in engagement with the outer surface of the member 94. A spring 106 resiliently urges the plunger 104 against the member 94 and an adjusting screw 108 permits a variable tension to be had on the spring 106. A lock nut 110 secures the screw in adjusted position. A piston 111, slotted to accommodate the plate 86 is provided with a groove 113 in the slot side wall adjacent the exhaust, and is axially movable in the chamber 82 with the member 94.

As the pressure in the pump builds up it is conducted to the outer surface 112 of the piston 111, through groove 113, and the pressure moves the piston 111 and member 94 against the tension of the spring 106. The effective width or pumping action of the member 94 is reduced or increased depending on the tension of the spring 106, and the pressure behind the surface 112.

In the forms shown in Figures 7 and 8 there is illustrated another modified form of a pump in which rotor members 114 are driven by meshed gears 116. One of the rotors is provided with an annular piston flange 118 which fits a bore 120 and forms a seal between the compartment for the rotors and the opposite end of the bore 120. Members 122 form seals at the ends of the rotors opposite the annular flange on one of the rotors; the one in the bore 120 being axially slidable

with the flanged rotor therein. A shaft 124 axially slidable but splined in one of the gears 116 moves the member and rotor axially in the bore 120 to vary the effective contact of the two rotors 114. In this form of the invention, means are provided for maintaining a constant pressure or supply at variable speeds of the pump since the pressure on the piston 118 exceeds the pressure on the upper member 122, the area of the member 122 in the bore 120 being less than that of the piston 118 due to the cut-out portion. The means comprises a link 126 pivoted as at 128 to a bracket 130 on the side of the housing 132. An adjustable weight 134 is placed on one end of the lever and the opposite end of the arm is yoked to the shaft 124 as at 136.

The weight provides a uniform pressure and does not increase its effect with increase in movement as in the case of a spring which is being compressed, and hence uniform pressure or output may be obtained.

Though several embodiments of the invention have been illustrated and described it is to be understood that the invention is not limited thereto, but may be embodied in various mechanical forms and combinations as may be desired. As various changes in construction and arrangement of parts may be made, for example substitution of the yielding means of one modification for the resilient means of another, and other rearrangements, without departing from the spirit of the invention, as will be apparent to those skilled in the art, reference will be had to the appended claims for a definition of the limits of the invention.

What is claimed is:

1. In a gear pump, a casing, a drive pinion therein, an idler pinion meshing therewith, and having a circular piston on one side thereof and means for preventing rotation thereof and a circular cutaway piston on the other side thereof, the said casing being recessed for rotary movement of said drive gear only, and recessed for rotary movement of said idler pinion and axial movement from its normal position in one direction only of said idler pinion and pistons, said

second named piston being cut away to closely clear said drive pinion, means for yieldingly urging said idler pinion into mesh with said driving pinion and in a direction toward the cutaway piston, an intake port leading towards the unmeshing teeth of said pinions, a discharge port leading away from the meshing teeth of said pinions, a port in the form of a groove on the outer surface of said first named piston leading from the unmoving teeth to the space on the opposite side thereof, and a port in the form of a groove on the outer surface of said second named piston leading from the meshing teeth to the space on the opposite side thereof.

2. In a gear pump, a casing having a drive bore, an idler bore parallel therewith and slightly intersecting the drive bore, a drive shaft concentric to said drive bore, a pinion closely fitting said drive bore and secured for rotation with said drive shaft and centrally located with respect to said drive bore, said drive bore being completely filled on one side of said pinion, and completely filled on the other side of said drive pinion except for a space defined by the idler bore, an idler pinion in the idler bore slidably from full engagement with the drive pinion to a point of partial engagement towards the said other side of said drive pinion, a non-circular piston on the one side of said idler pinion having a contour to fit the idler bore except for the intersecting drive bore, and a circular piston on the other side of said idler pinion, means for preventing rotation of said circular piston, an intake passage to said pinions, a discharge passage from said pinions, a port through said circular piston directly connecting the intake passage with the space in the idler bore on the other side of said circular piston from said idler pinion and a port through said non-circular piston directly connecting the space in said idler bore on the other side of said non-circular piston with the discharge port, and yielding means urging the idler pinion axially into full mesh with the drive pinion.

ANDREW O. MCCOLLUM.
